E. A. CONNER.

ANTISLIPPING SHOE FOR HORSES.

APPLICATION FILED NOV. 21, 1919.

1,380,705.

Patented June 7, 1921.

Edward A. Conner Inventor

UNITED STATES PATENT OFFICE.

EDWARD A. CONNER, OF BRIDGEPORT, CONNECTICUT, ASSIGNOR TO AMERICAN CHAIN COMPANY, INC., A CORPORATION OF NEW YORK.

ANTISLIPPING SHOE FOR HORSES.

1,380,705.

Specification of Letters Patent. Patented June 7, 1921.

Application filed November 21, 1919. Serial No. 339,580.

To all whom it may concern:

Be it known that I, EDWARD A. CONNER, a citizen of the United States, residing at Bridgeport, in the State of Connecticut, 5 have invented certain new and useful Improvements in Antislipping Shoes for Horses, of which the following, taken in connection with the accompanying drawing, is a specification.

10 The object of my invention is to provide a strong and simple strap buckle of such construction that the locking operation will be characterized by a take-up action which will serve to tighten the strap. A further 15 object is to provide such a buckle that will not cut or bruise the strap to be tightened and that can be used if desired with a plain strap having no perforations or peculiarities of construction. A still further object is to 20 provide a buckle which, in addition to the foregoing characteristics, may be readily manipulated although clogged with snow, ice, mud or similar matter.

Referring to the drawings: Figure 1 is 25 a view in perspective of my buckle in conjunction with a well known type of anti-slipping over-shoe for horses; Fig. 2 is a longitudinal section in elevation showing the buckle in unlocked position in conjunction 30 with attached straps; Fig. 3 is a longitudinal section in elevation showing the buckle in locked position in conjunction with attached straps; Fig. 4 is a detached top view of the base plate of the buckle; 35 Fig. 5 is a detached top view of the locking member thereof, and Fig. 6 is a longitudinal section in elevation of a modified form of my buckle.

Referring to Figs. 1 to 5 inclusive, on a 40 base plate 1 are located, approximately midway between ends thereof, suitable means for mounting a cam which may consist, for example, of two up-standing brackets 2-2, one on each lateral edge of the base plate. 45 One end of the base plate is adapted to be attached to an anchorage by means of the slot 3 and the other end is adapted to be connected with an end of a looped strap, preferably by means of another slot 4.

50 The locking member, which is in effect a bell crank or angle lever, consists of a cam 5 and a cam lever 6. The cam is provided with suitable means whereby it is adapted to be pivotally mounted between 55 the brackets, the said means as I provide

them consisting of the trunnions 7-7. The trunnions turn in the bearing 8 8 and their axis of rotation constitutes an axis on which the cam may oscillate. The radius of the cam, that is the distance from the axis to the 60 cam face 9 of the cam is less than the perpendicular distance from the axis to the base plate, clearance between the base plate and the cam face being necessary as hereinafter further described.

65 The angle which the lever 6 makes with the radial plane of the cam is such that the cam may be oscillated in an arc intersecting the perpendicular plane from the axis to the base plate and is preferably slightly in excess of 90 degrees. A further requirement that should be met in determining the degree of the angle is that when the cam is thrown into the position shown in Figs. 1 and 3, 70 which is the locked position, the plane of the cam will be in a plane slightly oblique to the perpendicular plane hereinbefore referred to, and the cam lever will have reached its maximum depression. In a buckle comprising parts having the relative shapes and proportions of those shown in the drawing, the angle should slightly exceed a right angle. It should be noted, however, that the essential feature is that the angle should be merely such as to permit the parts of the 75 locking member to be so disposed as to fulfil the requirements above described, and that provided these requirements are fulfilled, it is immaterial whether the angle be 80 acute or obtuse.

85 The cam lever is preferably provided at its free end with a transverse slot 9 of proper dimensions to permit a strap to be passed therethrough. I prefer that the cam lever should also be bent transversely of itself at some point intermediate its ends, whereby the free end will be slightly elevated as shown in Fig. 3 where the locked member is shown in locked position, the elevated end of the lever thus being easily 90 grasped by the fingers.

95 To illustrate the manner in which my buckle is applied, I have shown it in Fig. 1 in conjunction with an anti-slipping over-shoe for horses, anti-slipping over-shoes for 100 horses being appliances of such characteristics that very small differences in tautness make relatively great differences in correctness or incorrectness of adjustment.

105 Referring then to Fig. 1, a tension mem- 110

ber 10 is connected to the base plate, preferably by means of a flexible member 11 consisting of strap, another strap 12, one end of which is anchored to the slot 4 in the base 5 plate being looped through the tension member 13 and is then carried back to the buckle. The locking member being in open position as shown in Fig. 2, that is, the cam lever 6 having been swung so that the plane of the 10 cam is on the side of the perpendicular plane referred to, opposite to the side of that plane which the cam occupies in closed position, the strap is passed between the cam and the base plate and drawn as tightly as is 15 practicable by a direct pull.

The cam lever is then swung to the locked position as shown in Fig. 3. If preferred, the strap may after having been passed between the cam and the base plate, be passed 20 through the slot in the end of the lever and after being drawn tight, both strap and lever may be swung together with the lever to locked position. The thickness of the strap should be greater than the clearance 25 between the cam face and the base plate, so it will be seen that whether or not the strap is passed through the slot in the lever before locking, the strap will, as the lever is thrown over to locked position, be advanced 30 along the base plate a distance determined by that arc in the angular movement of the cam during which the cam compresses the strap against the base plate. The length of the arc mentioned may be considerably 35 increased if the base plate be bent upwardly as at 14. The compression of the strap will, it is seen, be at its maximum when the cam is in the perpendicular plane hereinbefore mentioned, becoming somewhat less as the 40 cam reaches its locking position. Tension on the strap when the cam is in its latter position therefore tends to increase the compression with a consequent increased resistance to the withdrawal of the strap as the 45 cam moves toward a position in the said perpendicular plane.

In the modified form of buckle shown in Fig. 6, I employ a base plate 15 similar to the base plate 1, except that in the modified 50 form I dispense with the slot 4, as the buckle may be used without a looped strap if desired. In this form, for the looped strap 12, is substituted the strap 16 adapted for a direct pull.

55 It will be apparent from a consideration of the principle of the invention that the same may be embodied in a variety of forms, all of which are intended to be included in the following claims:

60 1. In an anti-slipping shoe for horses, a tread portion provided with two free ends adapted to be drawn toward each other over the front of the hoof, one of said ends being provided with an eye, a strap buckle comprising a base plate provided at each end

with a strap anchorage, flexible connection between one of said anchorages and one of said free ends, a cam mounted on supports extending from said base plate, said cam being adapted to rotate on an axis parallel 70 with said base plate and transversely thereof, a cam lever provided at its free ends with a strap aperture, the radius of the cam being less than the perpendicular from said axis to said base plate, and the angle formed 75 by the lever of the cam being such as to permit said cam to be oscillated in an arc intersecting the said perpendicular, a strap anchored to the other of said anchorages and rove through an eye in the other of said 80 free ends, adapted to pass freely beneath said cam when the said lever is in elevated position and to be compressed between said cam and said base plate when the lever is in depressed position.

2. In an anti-slipping shoe for horses having a tread portion provided with two terminals adapted to be drawn toward each other over the front of the hoof, a buckle connected end to end with one of said terminals, a flexible member connected to the opposite end of said buckle adapted to be rove through an eye in the other of said terminals, said buckle comprising a base plate and a bell crank lever having a short 90 arm and a long arm disposed with respect to each other at an obtuse angle, said lever being pivotally mounted over said plate and transversely thereof and at such an elevation therefrom as to leave clearance between 95 the free end of said short arm and said plate, the amount of said clearance being such as to cause said flexible member to be compressed between said short arm and said plate when the long arm is depressed and 100 the said flexible member is passed between the said short arm and the said plate.

3. In an anti-slipping shoe for horses having a tread portion provided with two terminals adapted to be drawn toward each 110 other over the front of the hoof, a buckle connected end to end with one of said terminals, said buckle comprising a base plate and a bell crank lever having a short arm and a long arm disposed at an obtuse angle 115 with respect to each other, said lever being pivotally mounted over said plate and transversely thereof and at such an elevation from said plate as to leave clearance between the free end of said short arm and said plate, said long arm being provided with an eye at its free end and a flexible member connected to the opposite end of said buckle and adapted to be rove through an eye in the other of said terminals, thence 120 between said short arm and said base plate and thence through said eye in said long arm.

4. In an anti-slipping shoe for horses having a tread portion provided with two 130

terminals adapted to be drawn toward each other over the front of the hoof, a buckle comprising a base plate and a bell crank lever having a short arm and a long arm disposed at an obtuse angle with respect to each other, said bell crank lever being pivotally mounted over said plate and transversely thereof and at such an elevation from said plate as to leave clearance between the free end of said short arm and

the said plate, said long arm being provided at its free end with an eye whereby a strap having connection with the other of said terminals may be rove through the clearance space beneath said short arm and thence 15 through said eye.

In testimony whereof, I have signed this specification.

EDWARD A. CONNER.
